UNITED STATES PATENT OFFICE.

GLADYS R. FRISBEE AND FRANKLIN S. FRISBEE, OF CAMBRIDGE, MASSACHUSETTS.

GAME.

1,383,794.

Specification of Letters Patent. Patented July 5, 1921.

Application filed June 4, 1917. Serial No. 172,832.

To all whom it may concern:

Be it known that we, GLADYS R. FRISBEE and FRANKLIN S. FRISBEE, citizens of the United States, residing at Cambridge, in 5 the county of Middlesex and State of Massachusetts, have invented certain new and useful Improvements in Games, of which the following is a specification.

Our invention relates to improvements in 10 games and apparatus therefor, in which certain novel features are combined to produce an interesting and entertaining game for children or adults.

One of the objects of the invention is to 15 provide a game apparatus for playing a game having means for causing balls or other suitable objects to be projected from a holder, before which is placed a series of receptacles adapted to catch and hold such 20 balls as may fall into them.

Another object is to provide means for so 25 directing the balls, as they are projected from the holder, that they will fall in the direction of the receptacles in front of the holder.

Another object is to provide means external to the holder for controlling the action of the operating means within the holder.

Another object is to provide means co-operating with the controlling means external to the holder to jointly cause the action of the operating means within the holder.

Another object is to provide each of the 35 receptacles in front of the holder with a numerical or other designation, a few of which have a special value or significance.

Another object is to provide each of the 40 balls with a word or numerical designation adapted to coöperate with the designation on the receptacle into which it falls.

In the accompanying drawings Figure 1 is an isometric view of our improved game apparatus. Fig. 2 is a side elevation of the 45 game apparatus. Fig. 3 is a central cross section on the line $\alpha-\alpha$, Fig. 1. Fig. 4 is a central cross section of one of the special receptacles. Fig. 5 is a view of the weighted bag. Fig. 6 is a view of one of the balls. 50 Figs. 7 and 8 are cross sections of modified forms of the platform.

Latitude is allowed herein as to details, since they may be varied or changed at will without departing from the spirit or scope 55 of our invention.

Corresponding and like parts are referred

to in the following description and indicated in all the figures of the drawings by the same reference characters.

In the drawings 1 designates a base-board, 60 upon which is located a vertical holder 2, preferably cylindrical in form, adapted to hold on a platform or piston 3 balls 4 or other objects, made of wood or other suitable relatively light material, weighted, as indicated by the dotted lines in Fig. 6 showing a weight inserted therein, if so desired, so as to be drawn down by gravity and to fall more readily near the holder 2. The platform 3 is adapted to move freely within 65 the holder 2 and is provided with a rod 5 securely attached to its under side. Below the platform 3 is a guide plate 6 fixedly attached by any suitable means to the wall of the holder 2 and provided with an opening 70 7, through which the rod 5 is adapted to freely pass and thereby the guide-plate 6 acts as a guide in directing the movement of the rod 5 and the platform 3. The base of the holder 2 has fixedly attached thereto 75 a base-plate 8, by which the holder 2 is fastened to the base-board 1 preferably by means of a thumb-screw 9 or any other suitable means, so that the holder 2 may be detached for packing. The base-board 1 is 80 mounted on a frame 10, in order to elevate the whole structure above the floor on which it rests.

Pivoted to a block 11, which is fastened by a screw to the base-board 1 in front of 90 the holder 2, is an arm 12, which passes through an opening 13 in the holder 2. The outer end of the arm 12 is provided with a weight-receiver 14 or other suitable structure fastened thereto, comprising a base-plate 15 and an upright plate 16, while the inner end of the arm 12, extending within 95 the holder 2, is in contact with a disk 17 fastened to the lower end of the rod 5 adapted to provide ample contact surface for the 100 end of the arm 12, while near the upper end a block 18 is fastened, so as to give additional support to the platform 3, to which it is attached. A cap 19 surmounts the holder 2, to which it is attached by any suitable means, such as a paper band 20 glued thereto, so that it forms a part of the holder 2, and is provided in front with an opening 21, preferably elongated, through which the 105 balls 4 are projected, when the platform 3 is pushed upward. A deflecting plate 22, preferably transversely curved, is located 110

within the cap 19 and is inclined toward the opening 21, while it extends from the base of the cap 19 to the upper edge of the opening 21. The deflecting plate 22 is adapted 5 to deflect the balls 4, so that they will be directed and fall downwardly, when projected from the holder 2, toward receptacles 23 and special front receptacles 24 and special side receptacles 25 placed in positions difficult for a ball to enter. In the center of the upper edge of the opening 21 is a downwardly extending projection 26 adapted to aid in directing to either side of the opening 21 some of the balls 4 toward the receptacles 15 23 and particularly toward the special receptacles 24 and 25. The receptacles 23 are located preferably in receptacle-boards 27 and 28, which are attached to side boards 29 and 30 respectively, the receptacle-board 20 27 being detachable so that the arm 12 may be detached for packing, and provided with a front board 31 having an opening 32 through which the arm 12 extends, while the receptacle-board 28 is fastened to the base- 25 board 1 and has attached thereto a back-board 33, provided with an opening 34 for the arm 12, which coincides with the opening 13 of the holder 2, which is located behind the back-board 33. The special front 30 receptacles 24 are attached to the front corners of the base-board 1 and the special receptacles 25 are placed adjacent to the holder 2, and they are each provided with a circular diaphragm 35 of relatively thin, resonant 35 material inserted therein above the base, so that when a ball 4 enters one of the special receptacles 24 or 25 it will strike the diaphragm and by causing a sound will audibly indicate that the ball 4 has entered the 40 special receptacle.

While the platform 3 is preferably provided with a flat upper surface 36 adapted to coöperate with the deflecting plate 22 in directing the balls 4, in order to provide 45 means for aiding in controlling the balls so that they may be directed toward the various receptacles, when located at varying distances from the holder 2, detachable platforms 37 and 38, as shown in Figs. 7 and 50 8, may be provided having the flat surface 36 generally used on one side and an inclined surface 39 or concaved surface 40 on the other, the surfaces 39 and 40 being shown in Figs. 7 and 8 in operative position, so that 55 either the flat surface or the inclined or concaved surface may be used.

The receptacle-boards 27 and 28 are provided on their edges with upright strips 41 and 42 respectively, adapted to aid, when 60 struck by the balls, in directing the balls toward the receptacles and to prevent as much as possible the balls 4 from rolling or falling off the receptacle boards 27 and 28. A weighted bag 43 is adapted, when it 65 is thrown so as to strike or fall on the

weight-receiver 14, to cause the inner end of the arm 12 to be suddenly raised and to strike the rod 5, thereby throwing upward the platform 3 and causing some of the balls 4 thereon to be projected from the opening 21 70 down toward the receptacle-boards 27 and 28. Each ball 4 may, if so desired, have a number or a particular designation adapted to coöperate with the number or designation of the receptacle into which it falls. Since 75 several different modifications of the game may be employed, all of which will be based on the use of the holder 2 and the projecting of balls 4 therefrom, it is evident that in conjunction therewith separate receptacles 23, 24 and 25 may be used, instead of the receptacle-boards 27 and 28 with receptacles therein, and placed in any desired position with respect to the holder 2, or the balls 4 may be used alone without the receptacles and given, if so desired, numerical or other designations without departing from the basic and essential features of the game and the game apparatus. In order to add to the attractiveness and utility of the 80 game and game apparatus the holder 2, the receptacle-boards 27 and 28 and the back-board 33 as well as other parts may have thereon pictorial or other illustrations, showing any pictures or objects desired. 95

In playing the game with the apparatus a number of balls 4 are passed through the opening 21 into the holder 2 so as to rest on the platform 3. The receptacles 23 are given various numerical or other indications, 100 each indicating its particular value or significance in the game, for example as indicated in Fig. 1, while the special receptacles 24 and 25 placed in a difficult position for a ball to fall into are given a special value or 105 significance. The players stand at a certain specified distance from the front of the apparatus, which distance may be changed as desired, and each in turn throws the weighted bag 43 six times, for example, toward the 110 game apparatus, endeavoring each time to throw the weighted bag 43 onto the weight-receiver 14 and when this is done, the resulting action of the arm 12 causes the mechanism in the holder 2 to operate, as previously 115 described, thereby causing some of the balls 4 to be projected toward the receptacles 23 and 24 or 25. Every ball that enters a receptacle 23 or special side receptacles 25 gives a count on the score equivalent to the 120 number indicated for that receptacle, while every ball that is projected from the holder 2 falling and resting on the receptacle boards 27 and 28 or falling on the floor gives a lower count on the score. When a ball at 125 any time enters either of the special front receptacles 24 it gives the player the total number of points and the game. The number of points in the game may be placed at any desired figure, for example 100. More- 130

over, the balls 4 may each have a designation, either a word or number, which will coöperate with the number or word respectively, as the case may be, of the receptacle 5 into which it falls. Skill and care are necessary in throwing the weighted bag 43 so that the proper impetus will be given to the balls 4 and they will be projected in such a way that a number of them will fall into 10 the receptacles 23 or 25 and especially 24.

We claim:—

1. In a game apparatus, a holder, piston means operating within the said holder for causing balls to be projected from the said 15 holder, and inclined deflecting means co-operating with the said piston means and adapted to engage and deflect in various directions the said balls as they are about to leave the said holder.
2. In a game apparatus, a holder, piston means operating within the said holder for causing balls to be projected from the said holder, and transversely curved and inclined deflecting means coöperating with the 25 said piston means and adapted to engage and deflect in various directions the said balls as they are about to leave the said holder.
3. In a game apparatus, a holder, piston means operating within the said holder for causing balls to be projected from the said holder, and deflecting means inclined toward and coöperating with an opening in the said holder and adapted to engage and 30 deflect in various directions the said balls toward the said opening as they are about to leave the said holder.
4. In a game apparatus, a holder, piston means operating within the said holder for causing balls to be projected from the said holder, inclined deflecting means within the 40 said holder inclined toward and coöperating with an opening in the side of the said holder and adapted to engage and deflect 45 in various directions the said balls toward the said opening as they are about to leave the said holder.
5. In a game apparatus, a holder, piston means operating within the said holder for causing balls to be projected from the said holder, each of the said balls being provided with a weight, inclined deflecting means within the said holder inclined toward and coöperating with an opening in the side of the 50 said holder and adapted to engage and deflect in various directions the said balls toward the said opening as they are about to leave the said holder, and means for catching and holding the said balls.
6. In a game apparatus, a holder, piston means operating within the said holder for causing balls to be projected from the holder, inclined deflecting means within the 60 said holder inclined toward and coöperating with an opening in the side of the said 65

holder for deflecting and directing downwardly the balls from the holder toward receptacles, means external to the holder for controlling the said piston means, and means adapted to coöperate with the said external 70 means in jointly causing the action of the said piston means.

7. In a game apparatus, a holder, a piston comprising a platform for holding balls within the holder adapted to move freely 75 therein and provided with a rod depending therefrom, and means coöperating with the said rod in causing the said balls to be projected from the said holder.

8. In a game apparatus, a holder, a piston comprising a platform for holding balls within the holder adapted to move freely 80 therein and provided with a rod depending therefrom, a guide plate below the said platform having an opening therein through 85 which the said rod is adapted to move freely, and means coöperating with the said rod in causing the said balls to be projected from the said holder.

9. In a game apparatus, a holder, a piston 90 comprising a platform for holding balls within the holder adapted to move freely 95 therein and provided with a rod depending therefrom, a cap on the said holder provided with an opening therein, and means coöperating with the said rod in causing the said balls to be projected from the said holder through the said opening.

10. In a game apparatus, a holder, a piston comprising a platform for holding balls 100 within the holder adapted to move freely therein and provided with a rod depending therefrom, a pivoted arm, and a weight-receiver on one end of the arm and the other end extending within the holder and in contact with the end of the said rod.

11. In a game apparatus, a holder, a piston comprising a platform for holding balls adapted to move freely within the holder, and operating means for causing the said 110 platform to be thrown upward and the said balls to be projected from the holder.

12. In a game apparatus, a holder, a piston comprising a platform for holding balls adapted to move freely within the holder, a 115 cap on the said holder provided with an opening, and operating means for causing the said platform to be thrown upward and the said balls to be projected from the holder.

13. In a game apparatus, a holder, a piston comprising a platform for holding balls adapted to move freely within the holder, a cap on the said holder provided with an elongated opening, and operating means for 120 causing the said platform to be thrown upward and the said balls to be projected from the holder.

14. In a game apparatus, a holder, a platform for holding balls adapted to move 130

4
freely within the holder, a cap on the said holder provided with an opening having on its upper edge a downwardly extending projection, and operating means for causing the said platform to be thrown upward and the said balls to be projected from the holder.

15. In a game apparatus, a holder, a platform for holding balls adapted to move freely within the holder, a cap on the said holder provided with an elongated opening having on its upper edge a downwardly extending projection, and operating means for causing the said platform to be thrown upward and the said balls to be projected from the holder.

16. In a game apparatus, a holder, a piston having a platform for holding balls adapted to move freely within the holder, operating means for causing the said platform to be thrown upward and the said balls to be projected from the holder, and receptacles located in receptacle boards inclosed by raised walls for catching and holding the said balls provided with numerical or other designations.

17. In a game apparatus, a holder, a piston having a platform for holding balls adapted to move freely within the holder, a cap on the said holder provided with an opening, operating means for causing the said platform to be thrown upward and the said balls to be projected from the holder, and receptacles located in receptacle boards inclosed by raised walls for catching and holding the said balls provided with numerical or other designations.

18. In a game apparatus, a holder, a piston having a platform for holding balls adapted to move freely within the holder, a cap on the said holder provided with an elongated opening, operating means for causing the said platform to be thrown upward and the said balls to be projected from the holder, and receptacles located in receptacle boards inclosed by raised walls for catching and holding the said balls provided with numerical or other designations.

19. In a game apparatus, a holder, a piston having a platform for holding balls adapted to move freely within the holder, a cap on the said holder provided with an opening having on its upper edge a downwardly extending projection, operating means for causing the said platform to be thrown upward and the said balls to be projected from the holder, and receptacles located in receptacle boards inclosed by raised walls for catching and holding the said balls provided with numerical or other designations.

20. In a game apparatus, a holder, a piston having a platform for holding balls adapted to move freely within the holder, a cap on the said holder provided with an elongated opening having on its upper edge

a downwardly extending projection, operating means for causing the said platform to be thrown upward and the said balls to be projected from the holder, and receptacles for catching and holding the said balls provided with numerical or other designations.

21. In a game apparatus, a holder, a platform for holding balls adapted to move freely within the holder, operating means for causing the said platform to be thrown upward and the said balls to be projected from the holder, and a deflecting plate within the holder adapted to deflect the course of the said balls as they are about to leave the holder.

22. In a game apparatus, a holder, a platform for holding balls adapted to move freely within the holder, a cap on the said holder provided with an opening, operating means for causing the said balls to be projected from the holder, and a deflecting plate within the holder adapted to deflect the said balls as they are about to leave the holder through the said opening.

23. In a game apparatus, a holder, a platform for holding balls adapted to move freely within the holder, a cap on the said holder provided with an elongated opening, operating means for causing the said platform to be thrown upward and the said balls to be projected from the holder, and a deflecting plate within the holder adapted to deflect the said balls as they are about to leave the holder through the said elongated opening.

24. In a game apparatus, a holder, a platform for holding balls adapted to move freely within the holder, operating means for causing the said platform to be thrown upward and the said balls to be projected from the holder, receptacles for catching and holding the said balls provided with numerical or other designations, and a deflecting plate within the holder adapted to deflect the course of the said balls as they are about to leave the holder toward the said receptacles.

25. In a game apparatus, a holder, a piston having a platform for holding balls adapted to move freely within the holder, operating means for causing the said platform to be thrown upward and the said balls to be projected from the holder, receptacles for catching and holding the said balls and having certain numerical or other designations, and special receptacles having particular or other distinctive designations and located respectively on each side and in front of the said holder.

26. In a game apparatus, a holder, a platform for holding balls adapted to move freely within the holder, operating means for causing the said platform to be thrown upward and the said balls to be projected from the holder, receptacles for catching

- and holding the said balls, and special receptacles having diaphragms adapted to audibly indicate when a ball has entered therein.
- 5 27. In a game apparatus, a holder, a piston having a platform for holding balls and adapted to move freely within the holder, a cap on the said holder provided with an opening, operating means for causing the 10 said platform to be thrown upward and the said balls to be projected from the holder, receptacles for catching and holding the said balls and having certain numerical or other designations, special receptacles having particular or other distinctive designations and located respectively on each side and in front of the said holder, the said special receptacles having diaphragms adapted to audibly indicate when a ball has entered therein, and a deflecting plate within the said holder adapted to deflect the course of the said balls as they are about to leave the holder and direct them toward the said receptacles.
- 15 28. In a game apparatus, a holder, piston means operating within the said holder for causing balls to be projected from the 20 25
- said holder, inclined deflecting means within the said holder inclined toward and co-operating with an opening in the side of the said holder and adapted to engage and deflect in various directions the said balls toward the said opening as they are about to leave the said holder, and means for catching and holding the said balls.
29. In a game apparatus, a holder, piston means operating within the said holder for causing balls to be projected from the 30 35 40 45 said holder, inclined deflecting means within the said holder inclined toward and co-operating with an opening in the side of the said holder and adapted to engage and deflect in various directions the said balls toward the said opening as they are about to leave the said holder, and means external to the holder for controlling and operating the said piston means.

In testimony whereof we have affixed our signatures, in the presence of two witnesses.
